(57) **CLAIM**

The ornamental design for a turkey hunter's gun rack, as shown and described.

DESCRIPTION

FIG. 1. is a top plan view of the turkey medallion portion of the turkey hunter's gun rack;

FIG. 2. is a right side elevation thereof;

FIG. 3. is a bottom plane view thereof;

FIG. 4. is a left side elevation thereof;

FIG. 5. is a frontal plane view thereof;

FIG. 6. is a top plane view of the gun holder portion of the turkey hunter's gun rack;

FIG. 7. is the frontal plane view thereof;

FIG. 8. is the bottom plane view thereof;

FIG. 9. is a left side elevation of the gun holders thereof;

FIG. 10. is a right side elevation of the gun holders thereof;

FIG. 11. is an exploded view of the turkey medallions and the turkey feet gunholders; and,

FIG. 12. is a right side elevation of the assembled turkey hunter's gun rack; the left side elevation is a mirror image of FIG. 12.

The Turkey Hunter's Gun Rack is mounted to a stable surface by screwing the gun holders through the hole at the bottom of the turkey medallions until the gun holder firmly holds the turkey medallion to the mounting surface. The long gun is then placed in the upright gun holders for display.
